US00D984537S

(12) United States Design Patent (10) Patent No.: US D984,537 S
(45) Date of Patent: * Apr. 25, 2023

(54) SET OF ACCESSORIES FOR VIDEO GAMES

(71) Applicant: Endor AG, Landshut (DE)

(72) Inventor: Bernhard Conrad, Buch am Erlbach (DE)

() Term: 15 Years

(21) Appl. No.: 35/514,096

(22) Filed: Dec. 8, 2021

(80) Hague Agreement Data

Int. Filing Date: Dec. 8, 2021

Int. Reg. No.: DM/220109

Int. Reg. Date: Dec. 8, 2021

Int. Reg. Pub. Date: Apr. 22, 2022

(30) Foreign Application Priority Data

Jun. 9, 2021 (EM) 008570113-0001

(51) LOC (14) Cl. 21-01

(52) U.S. Cl.

USPC D21/333; D12/177

(58) Field of Classification Search

USPC D12/174, 177, 179-180; D21/333

See application file for complete search history.
